UNITED STATES PATENT OFFICE.

JOSEPH SAGAN, OF PITTSBURGH, PENNSYLVANIA.

FLUSHING-CONDUIT.

1,255,648.

Specification of Letters Patent. Patented Feb. 5, 1918.

Application filed February 27, 1917. Serial No. 151,237.

To all whom it may concern:

Be it known that I, JOSEPH SAGAN, a subject of the Emperor of Austria-Hungary, residing at No. 208 Pine street, North Side, 5 Pittsburgh, in the county of Allegheny and State of Pennsylvania, have invented a new and useful Flushing-Conduit, of which the following is a specification.

This invention relates to a flushing conduit arranged to be installed in the centers 10 of streets or roadways.

One object of the invention is to provide a flushing conduit which may be permanently installed, and which is arranged to 15 project a substantially unbroken stream or sheet of water into the street along the entire length of the conduit in such manner that it will flush the same on both sides of the conduit from points immediately adjacent thereto outwardly to the sides or gutters of the street. A further object of the 20 invention is to provide a conduit which, in addition to the advantages above stated, is so arranged that it is normally in position 25 to perform the flushing operation, and which is adequately protected from the jars and stresses of traffic.

In the accompanying drawings, Figure 1 is a diagrammatic plan view illustrating a 30 plurality of intersecting streets and the position in which the flushing conduit is designed to be placed therein; Fig. 2 is a plan view with parts broken away showing a portion of the conduit in position in a street 35 or roadway; and Fig. 3 is a cross sectional view on the line 3—3 Fig. 2.

In order to illustrate the adaptability of the conduit to the conditions existing in city streets, Fig. 1 shows a plurality of intersecting streets 1, 2, and 3 with blocks of buildings 4 arranged therealong, and the conduit indicated at 5 laid in the center of the streets. As shown, the conduit may be laid 45 between the tracks of a single car line, as shown in the street 3, or between the lines of a double tracked street 1, the street 2 having no car track thereon. When thus installed the sections or systems of conduit may receive water from any convenient 50 source, as from hydrants diagrammatically indicated at 6, or the system of conduit may be continuous and supplied from a single adequate source.

The conduit comprises a pipe of semi-cylindrical form arranged to be contained 55 in a casing 8, which is in the form of a block

having a longitudinal cavity 9 of greater dimensions than those of the pipe and arranged to provide a space between the pipe and casing so as to permit of a slight vertical movement of the pipe therein; the casing being provided with a footing 11 embedded in the structure 10 of the street. The casing 8 is provided with a pair of longitudinal projections 8^a which extend 60 into the longitudinal cavity or channel 9 of the casing and contact the pipe in its normal or raised position therein. On the upper, and substantially plane, surface 12 of the pipe 7 is a guard member 13, secured thereto by suitable bolts or set screws 14 and projecting slightly beyond the sides of the pipe. This guard member also serves to spread 65 and direct jets of water issuing from the orifices 15, which are located immediately 70 beneath the upper surface 12 on both sides of the pipe. These outlets or orifices 15 are upwardly and outwardly inclined and flare 75 downwardly and outwardly; the guard 13 being provided at its lateral extremities 80 with short depending portions 16 overlying the orifices 15, and with grooves 16^a in its under surface arranged to match with the orifices. By means of this construction the 85 water does not issue from the conduit in jets, but is spread and directed along the surface of the street or roadway from the mouths of the orifices in a substantially unbroken stream or sheet, so that the full 90 cleansing effect is obtained throughout the 95 entire width of the street on both sides of the conduit and no objectionable upwardly directed jet or spray is produced.

In order to yieldingly support the pipe 7 in its upward or operative position, it is 95 provided at intervals along its lower face with a plurality of stems 17 resting upon relatively strong helical springs 18 in recesses 19 in the casing 8. By means of the springs 18 the pipe is normally maintained 100 in its raised position projecting slightly above the upper extremity of the casing, but upon the passage of vehicles over the pipe it is so depressed, against the resistance of the springs, that the depending portions 105 16 of the guard rests upon the upper surface of the casing which is slightly beveled along its inner edges. The upper surface of the guard 13 then lies substantially flush with the surface of the street or roadway 110 and protects the pipe from injury. In its raised or operative position the pipe is pro-

ected from lateral displacement in the casing by means of the portions 8^a projecting into the cavity or channel 9 in which the pipe lies, and is thus protected from injury due to jarring of the pipe against the interior of the casing. This engagement between the pipe 7 and the projections 8^a also serves in some degree to prevent the entrance of refuse into the space between the 10 pipe and the casing.

It will be thus seen that the flushing conduit above described is one which lies normally in operative position, and which requires no manual operation to raise the same 15 for use or to depress it for protection against injury. It is, moreover, so arranged that water is projected in a stream or sheet throughout the entire length of the conduit from both sides thereof, and from a point 20 immediately adjacent the conduit, so that the street or roadway is flushed from its crown outwardly to the gutters by means of a current directed toward the sides of the street. The conduit is moreover so arranged 25 that no upward jets or sprays are caused and the flushing effect is uniform from the sides of the conduit itself outwardly to the sides or gutters of the street or roadway. The construction of the conduit is simple and 30 such that the pipe may be readily removed from position in the street for repairs or replacement or for cleansing of the cavity in the casing in which the pipe lies.

What I claim is:—

- 35 1. A flushing conduit comprising a horizontally disposed casing having its upper extremity substantially flush with the surface of the ground in which it is laid, a pipe provided with discharge orifices adjacent 40 the upper face thereof in said casing, a guard secured to the upper face of said pipe, and resilient means arranged to normally support said pipe with its upper face projecting above the upper extremity of said casing.
- 45 2. A flushing conduit comprising a horizontally disposed casing having its upper extremity substantially flush with the surface of the ground in which it is laid and having longitudinal projections extending 50 interiorly thereof, a pipe in said casing provided with discharge orifices adjacent the upper face thereof, and resilient means ar-

ranged to normally support said pipe in contact with said projections and with its upper face projecting above the upper extremity of 55 said casing.

3. A flushing conduit comprising a horizontally disposed pipe provided with discharge orifices adjacent its upper face, a guard secured to said pipe and overlying 60 said orifices, and resilient means for yieldingly supporting said pipe in operative position relative to the surface of the ground in which it is laid.

4. A flushing conduit comprising a horizontally disposed casing having vertical recesses therein, resilient members in said recesses, and a pipe in said casing, said pipe being provided with discharge orifices and with stems arranged to enter the recesses in 70 said casing and contact the resilient members therein.

5. A flushing conduit comprising a horizontally disposed casing having its upper extremity substantially flush with the surface 75 of the ground in which it is laid and having vertical recesses therein, resilient members in said recesses, a pipe provided with discharge orifices adjacent its upper face and having stems arranged to extend into said 80 vertical recesses and contact the resilient members therein, and a guard secured to said pipe and overlying said orifices.

6. A flushing conduit comprising a horizontally disposed casing having its upper 85 extremity substantially flush with the surface of the ground in which it is laid and provided with longitudinal projections extending interiorly thereof and with vertical recesses, resilient members in said recesses, a 90 pipe in said casing provided with discharge orifices adjacent the upper face thereof and having stems extending into said recesses and contacting the resilient members therein whereby said pipe is normally supported in 95 contact with said projections and with its upper face projecting above the upper extremity of said casing.

In testimony whereof, I affix my signature in the presence of two witnesses.

JOSEPH SAGAN.
